DISPLAY BOX

Richard R. Holcomb, Chicago, Ill., assignor to
Wm. Wrigley Jr. Company, Chicago, Ill., a cor-
poration of Delaware

Application December 3, 1936, Serial No. 114,019

5 Claims. (Cl. 206—44)

This invention relates to improvements in display boxes, and consists of the matters herein-after described and more particularly pointed out in the appended claims.

5 The object of the invention is to produce a display box of simple and economical construction, capable of manufacture from a single blank of cardboard or heavy paper, and which when opened up for display purposes will present the articles contained therein on an upwardly and rearwardly inclined inner bottom, with a card for advertising purposes extending above the rear end of the box.

10 The objects and advantages of the invention will appear more fully as I proceed with my specification.

In the drawings:

Figure 1 is a plan view of a blank of cardboard or heavy paper cut and scored in manner to form the improved display box.

Figure 2 is a perspective view of the box as it appears in display position.

Figure 3 is a view representing a vertical central section through the box in the plane indicated by the line 3—3 of Figure 2.

Figure 4 is a perspective view of the blank shown in Figure 1, with the parts as they appear when the required manipulation to fold the blank to box form has been started.

30 Figure 5 is a perspective view showing the blank at a further stage of the process of folding it to box form.

Figure 6 is a transverse section through the box in a plane indicated by the line 6—6 of Figure 3.

35 Referring now to that embodiment of the invention illustrated in the drawings: 10 indicates the box-forming blank which is cut and scored as shown in Figure 1; 11 indicates the bottom wall; 12 indicates the front wall, and 13 indicates the rear wall. Said parts are laid out on the blank end to end and defined endwise by transverse score lines 12^a, 13^a.

40 The blank includes side members 14, 14 which are scored and cut alike. 15, 15 indicate longitudinal score lines which divide the side members 14, 14 from the front wall 12, and 15^a, 15^a indicate cuts (in line with said score lines) which sever said side members from the bottom wall 11. The transverse score line 12^a dividing the front wall 12 from the bottom wall 11 is extended laterally across the side members 14, 14 beyond the score lines 15 as indicated at 12^b, 12^b to define the bottom limits of side walls 16, 16. 16^a, 16^a indicate the top edges of the side walls 16. They are cut 45 at angle to the top edge 12^c of the end wall 12,—

being inclined away from prolongations of the line of said edge, as clearly shown in Figure 1.

45 17, 17 indicate parts of the side members 14, 14 of the blank beyond the score lines 12^b, 12^b. Said parts 17, 17 are free of the blank along the cuts 15^a, 15^a. Each of said parts is provided with spaced transverse lines adapting it to be folded upon itself to form a wedge-like tubular member adapted to occupy one-half of the bottom 11 of the box and to present a supplemental inner bottom wall which inclines upwardly from the front towards the rear wall of the box. 17^a, 17^a indicate score lines spaced half the width of the box bottom 11 from the score lines 12^b, 12^b, which define the bottom edges of the side walls 16, 16. 15 18, 18 indicate score lines spaced from and diverging from the score lines 17^a, 17^a towards the outer edges of the parts 17, 17. 19, 19 indicate score lines extending parallel to and spaced from the score lines 18, 18, distances equal to the spaces 20 between the score lines 17^a and 12^b. 20, 20 indicate score lines disposed at the same angles to the score lines 19 as the score lines 18 to the score lines 17^a, leaving narrow flap extensions 21, 21 beyond the score lines 20. The edges of the parts 25 17 beyond the score lines 18 are cut at right angles to said score lines 18, 18.

Beyond the rear wall 13 the blank is provided with a display extension 22 defined by a score line 22^a. At the sides of the end wall 13 are narrow 30 flaps 23, 23 and 24, 24 defined by score lines 25, 25 and separated from each other by cuts 26, 26.

To assemble the box, one of the parts 17 of the side members 14 of the blank is folded upon itself along the score lines 20, 19, 18 and 17^a as 35 shown in Figure 4, and along the score line 12^b to form a hollow, wedge-like member, as shown at the left in Figure 5, with one side engaged against the proximate side wall 16 of the box, with its bottom in the plane of the bottom edge of 40 said side wall and its top presenting an inclined inner bottom wall section. The other part 17 is folded in like manner with respect to its proximate side wall 16 and then each side wall is swung upon the score line 15 to bring the two supplemental wedge-like bottom members 21, 21, to 45 position on the bottom wall 11 as shown in Figure 6.

The rear wall 13 is now swung upright with reference to the bottom wall 11 on the score line 13^a. 50 In this operation the flaps 24 near the bottom of the rear wall 13 are folded in and engaged within the open ends of the hollow wedge members 21, thus acting to hold said members in open relation; and the flaps 23 are folded against the up- 55

right margins of the side walls 16, all as shown in Figure 3. Any suitable means, preferably an adhesive, as glue, may be used for attaching the flaps 23 to the inside margins of the side walls 16, 16.

5 The box is now ready for packing, and after packing the display extension 22 may be folded down about the score line 23 upon the contents of the box.

10 It will be noted that by reason of the angle at which the top edges 16^a of the side walls 16 are disposed to the top edge 12^c of the front wall 12, said edges when the box is set up incline upwardly and rearwardly. It will be further noted that 15 because of the angles at which the score lines 18, 19 and 20 are disposed to the score lines 17^a and 12^b of the blank, the top faces of the supplemental bottom members 27, 27 incline upwardly and rearwardly at an angle substantially parallel to the top edges 16^a, 16^a of the side walls of the box.

20 Obviously the blanks to form the box may be shipped flat, and may be easily and quickly manipulated to set up the box as required by the 25 packer.

When the goods are packed in the box, the display flap 22 may be folded down on top of them in the usual manner,—wax paper or other covering being used to cover that part of the contents not covered by said flap. The box may then be packed in a slip-cover as usual for shipment,—a filler being provided to compensate for the inclined top edges of the box.

25 The hollow wedge members 27 substantially filling as they do the bottom of the box with their proximate edges engaged against each other, and their outer edges engaged against the upright side walls 16, 16 of the box, provide a very rigid construction. This not only presents a box comparatively rigid against lateral compression at 30 the bottom, but also an inner bottom which is not easily distorted by the weight of the contents or otherwise. The proximate edge parts of the tubular wedge-shaped members together presented an efficient strut for supporting the inclined inner bottom wall along its longitudinal median line.

35 I claim as my invention:

1. A display box comprising front, bottom and 40 rear walls hinged together in end-to-end relation, said rear wall being of greater depth than said front wall, side walls hinged to the lateral edges of said front wall and having edges at an angle to the edge of said front wall, blank parts hinged 45 to the bottom of said side walls but otherwise free,

5 said blank parts being cut and scored to fold upon themselves to form tubular wedge members adapted to lie upon the bottom wall to provide an upwardly and rearwardly inclined inner wall, and said rear wall having upper and lower lateral flaps, said lower flaps being adapted for engagement within the open rear ends of said tubular wedge members when the box is set up.

2. A display box made from a blank cut and 10 scored to provide front, bottom and rear walls, and a display member extending in end-to-end relation, said end wall being of greater depth than said front wall, side walls at the lateral edges of said front wall with their free edges at an angle to the free edge of said front wall, said blank including parts hinged to the bottoms of 15 said side walls but otherwise free, said parts being cut and scored to fold upon themselves to form tubular wedge members adapted to lie upon the bottom wall to provide an upwardly and rearwardly inclined inner wall, and top and bottom flaps at the lateral edges of said rear wall, said bottom flap being adapted for engagement within 20 the open rear ends of said tubular wedge members when the blank is set up into box form.

25 3. A box made from a blank cut and scored to form front, bottom, side and rear walls, said blank including parts cut and scored to be folded upon themselves to provide tubular members adapted to lie upon the bottom of the box, said tubular members having sides abutting the side-walls of the box and sides abutting each other intermediate said side walls of the box and presenting an inner supplemental bottom wall.

30 4. A box made from a blank cut and scored to form front, bottom, side and rear walls, said blank including parts cut and scored to be folded upon themselves to provide tubular wedge-shaped members adapted to lie upon the bottom of the box, said tubular members having sides abutting the side walls of the box and sides abutting each other intermediate said side walls of the box and 35 presenting an inner supplemental bottom wall.

40 5. A box made from a blank cut and scored to form front, bottom, side and rear walls, said blank including parts cut and scored to be folded upon themselves to provide tubular members of like width and cross section to lie upon the box bottom and present an inner supplemental bottom wall, said tubular members having sides 45 abutting the side walls of the box and proximate sides abutting together and extending substantially the length of the box bottom.

RICHARD R. HOLCOMB. 55
